(57) **CLAIM**

The ornamental design for a splash guard for a beverage dispenser holster, as shown and described.

DESCRIPTION

FIG. 1 is a perspective view of a splash guard according to our invention;

FIG. 2 is a top view of the splash guard of FIG. 1;

FIG. 3 is a bottom view of the splash guard of FIG. 1;

FIG. 4 is a front plan view of the splash guard of FIG. 1;

FIG. 5 is a rear plan view of the splash guard of FIG. 1;

FIG. 6 is a right side view of the splash guard of FIG. 1;

FIG. 7 is a left side view of the splash guard of FIG. 1;

FIG. 8 is a perspective view of the splash guard prior to insertion in a beverage dispenser holster, with the beverage dispenser holster illustrated in broken lines to show environmental features; and,

FIG. 9 is a perspective view of the splash guard inserted in the beverage dispenser holster, with the beverage dispenser holster illustrated in broken lines to show environmental features.

The broken lines illustrate environmental structure and form no part of the claimed design.

1 Claim, 6 Drawing Sheets
